UNITED STATES PATENT OFFICE

153,416

DESIGN FOR A LIGHTER

Albert J. Bruneau, Montreal, Quebec, Canada

Application January 22, 1947, Serial No. 136,287
In Canada January 2, 1947

Term of patent 3½ years

(Cl. D48—24)

To all whom it may concern:

Be it known that I, Albert J. Bruneau, a Canadian, residing at Montreal, in the Province of Quebec, Dominion of Canada, have invented a new, original, and ornamental Design for Lighter, of which the following is a specification, reference being had to the accompanying drawing, forming part thereof.

Figure 1 is a plan view of the lighter showing my new design.

Figure 2 is a front elevation of the lighter.

Figure 3 is a side elevation of the lighter.

Figure 4 is a rear elevation of the lighter.

Figure 5 is a side elevation of the lighter in the open position.

I claim:

The ornamental design for a lighter, as shown.

ALBERT J. BRUNEAU.
